UNITED STATES PATENT OFFICE

MIDGLEY W. HILL, OF FLUSHING, NEW YORK

INFORMATION DEVICE FOR AUTOMOBILES

Application filed April 6, 1929. Serial No. 353,123.

This invention relates to a device for use on automobiles, and has for its primary object the provision of a casing or holder adapted to be supported in a convenient position within an automobile or like vehicle, and having suitable indicia within the casing which may be readily displayed with a view of discouraging theft by apprising those concerned, including the purchaser of second hand cars, with complete history regarding the particular vehicle.

A salient object of this invention is to provide a device of the above mentioned character which will be compact in construction, simple in operation, capable of easy assembly and attachment in a convenient position within the automobile, simple in operation, thoroughly practical and efficient in use.

Other objects and advantages of the invention will become apparent during a study of the following description taken in connection with the accompanying drawings, wherein:

Figure 1 is an elevation showing my improved device secured to the dash board of an automobile,

Figure 2 is an enlarged elevation of my device showing it secured to another convenient part of, and within the automobile,

Figure 3 is a transverse sectional view taken through the casing and supporting structure,

Figure 4 is a detail perspective of the web movable within the casing,

Figure 5 is a detail sectional view taken through one end of the casing and showing my improved operating means for the device.

In the contemplated embodiment of my invention and as herein illustrated, there is provided a rectangular box like casing 5 formed of metal or other strong material, said casing 5 comprising the back plate 6 having a marginal flange 7 extending therearound to provide a peripheral wall for the casing.

The wall 7 is further provided with a flange 8, while a cover plate 9 having a transverse opening 10 formed therein is secured to the casing as at 11. Formed within the casing opposite the opening 10 and the cover plate 9 there is a transversely extending guide

plate 12, the ends of which guide plate are secured to the peripheral wall 7 in any well known or conventional manner.

Journalized within the casing is a pair of spaced rollers or drums 13, and these rollers or drums are disposed one above and the other below the opening 10. The peripheral surface of each of the rollers is notched as at 14 and 15 respectively, while an elongated web 16 is provided at its opposite end with tabs 17, each of said tabs having openings 18 formed therein.

As best shown in Figure 3 one of the tabs 17 is disposed within the notch 14 and a suitable fastening element such as a tack 19 is passed through the opening in the tab and embedded within the roller, the webs then being wound about the roller for several times then directed upwardly between the opening 10 and the guide plate 12 so that the other end of the web may have the tab carried thereon secured to the roller 15 in a manner similar to that described with regard to the before described roller.

This manner of securing the web to the roller has been described merely by way of exemplification, since it is understood that there are various ways of so securing the roller and web in operative relation. Upon the web 16 there is printed or otherwise fashioned information of interest and advantage to the occupants of the car, such information being in the form of data regarding the manufacturer, the car and motor number, dealer's name, and the address of the present and subsequent owners, together with the names of the said owners.

Attention is now directed to Figure 5 wherein is illustrated the preferred means of operating the rollers so as to selectively align the data on the web 16 with the opening 10 in the base plate of the casing. In this connection then it will be seen that the rollers 13 are provided at one end with circular gears 20, while a disk 21 provided on its periphery with teeth 22 is journalized within the casing intermediate the rollers and in operative association therewith to permit the teeth 22 on the disk to engage with the teeth on the respective gears for rotating the rollers where-

by the desired data on the web may be presented to view through an elongated opening in the base plate.

The preferred manner of associating my improved information device to the vehicle is best shown in Figures 1 and 2, and more in detail in Figure 3. It is to Figure 3 that I now direct attention and therein I have designated the instrument board generally by the reference character 23.

10 The instrument board 23 is provided with an elongated opening 24 and the assembled casing is secured to the rear face of the said instrument board and fixed thereto as at 25 so that the opening formed in the cover plate is in alinement with the opening 24 on the instrument board.

15 A suitable frame, preferably formed of metal is secured to the instrument board and surrounds the opening formed therein, while 20 a transparent panel, preferably formed of glass, and designated by the numeral 25 is disposed within the frame and over said opening, and is secured thereto by means of 25 screws 26 passing through the frame and glass at the corners of the frame and glass.

20 Attention is also called to the fact that one of the side members of the frame is provided with an opening 27, and that the toothed-disk 21 extends exteriorly of the casing through an opening 28 formed within the cover plate, the opening 29 formed in the instrument board and the said opening 27 in the frame, so that the said disk may be rotated by application of the thumb or finger thereto in a well known manner.

25 From the foregoing then it will be seen that I have provided a novel means of supplying the occupants of an automobile with information and data relative to the particular vehicle, and whereby those concerned may readily acquaint themselves with such information as regards the manufacture of the car, the number of the car and the motor, and other such information which may be of interest to the reader.

30 While I have herein shown and described certain structural features and advantages of my invention, it is to be understood that 59 certain changes may be made therein, without departing from the spirit of the invention as described or the scope of the appended claim.

35 Having thus described my invention, what I claim as new is:

40 In combination, an automobile embodying an instrument board, said instrument board having an elongated opening formed therein, a casing carried by said instrument board 60 and provided with an opening adapted for alignment with the opening in the instrument board, a guide plate in said casing rearwardly of said opening, a pair of drums rotatable in the casing, a web operatively associated with the drums and having suitable

information inscribed thereon for selective alinement with said openings, a frame including vertical side members surrounding the opening in the instrument board and having a transparent medium disposed 70 therein, said frame having an elongated opening formed in a side member thereof and the instrument board and casing having corresponding openings in alinement with said frame opening, a disk rotatable within the 75 casing and provided with teeth on the periphery thereof in mesh with the gears on each of said drums for rotating the drums, said disk extending through the opening in the frame and the alined openings in the instrument board and casing to expose a portion thereof for operative engagement.

80 In testimony whereof I affix my signature.
MIDGLEY W. HILL.
